UNITED STATES PATENT OFFICE.

HENRY L. HASKELL, OF LUDINGTON, MICHIGAN.

DESIGN FOR A GAME-BOARD.

SPECIFICATION forming part of Design No. 31,018, dated June 13, 1899.

Application filed May 13, 1899. Serial No. 717,010. Term of patent 14 years.

To all whom it may concern:

Be it known that I, HENRY L. HASKELL, a citizen of the United States, residing at Ludington, in the county of Mason and State of Michigan, have invented a certain new and original Design for Game-Boards; and I do hereby declare the following to be a full, clear, and exact description of the invention, such as will enable others skilled in the art to which it appertains to make and use the same.

Figure 1 is a perspective view of the obverse of my game-board. Fig. 2 is a section taken through the center of the board, and Fig. 3 is a plan view of the reverse of the board.

The board has a flat or plane face with a central spot and base-lines, from which the play of the disks used in the game may be directed, an outer rim projecting above and below the face to retain the playing-disks and to serve as a foundation for a carom-cushion,

and the board has in this example curved corners. In each of the corners, outside the base-line, is a circular opening to receive a pocket.

The reverse of the board has the projecting rim, the face, and the circular openings of the obverse, and has in the center a raised circular piece with concentric circular lines upon the surface and a central depression or pocket surrounded by projecting pins.

Having fully described my invention, what I claim, and desire to secure by Letters Patent, is—

The design for a game-board as herein described and illustrated.

In testimony whereof I affix my signature in presence of two witnesses.

HENRY L. HASKELL.
